US0D1080456S

(12) **United States Design Patent** (10) **Patent No.:** **US D1,080,456 S**
(45) **Date of Patent:** **** Jun. 24, 2025**

(54) **CHAIN FOR SLIDE FASTENER**

(71) Applicant: **YKK Corporation**, Tokyo (JP)

(72) Inventors: **Kohei Kawarada**, Toyama (JP);
Hisatomo Sugita, Toyama (JP); **Jun
Shitaka**, Toyama (JP)

(73) Assignee: **YKK Corporation**, Tokyo (JP)

(**) Term: **15 Years**

(21) Appl. No.: **29/890,403**

(22) Filed: **Apr. 24, 2023**

(30) **Foreign Application Priority Data**

Nov. 4, 2022 (JP) ..... 2022-023946 D

(51) **LOC (15) Cl.** **02-07**

(52) **U.S. Cl.**

USPC **D11/221**

(58) **Field of Classification Search**

USPC D11/200, 221; D2/853

CPC A44B 19/00-406; A41F 1/008

See application file for complete search history.

Primary Examiner — Brett Miller

Assistant Examiner — Sara Michie Pottenger

(74) *Attorney, Agent, or Firm* — Kilpatrick Townsend & Stockton LLP

(57) **CLAIM**

The ornamental design for a chain for slide fastener as shown and described.

DESCRIPTION

FIG. 1 is a perspective view of a chain for slide fastener showing our new design;

FIG. 2 is a front view thereof;

FIG. 3 is a rear view thereof;

FIG. 4 is a left side view thereof;

FIG. 5 is a right side view thereof;

FIG. 6 is a top view thereof, and,

FIG. 7 is a bottom view thereof.

1 Claim, 7 Drawing Sheets
